UNITED STATES PATENT OFFICE

97,127

DESIGN FOR A FRUIT BASKET

James H. Fuller, Akron, Ohio, assignor to D'Or
Studios, Inc., Akron, Ohio, a corporation of Ohio

Application November 15, 1934, Serial No. 54,024

Term of patent 7 years

To all whom it may concern:

Be it known that I, James H. Fuller, a citizen of the United States, residing at Akron, in the county of Summit and State of Ohio, have invented a new, original, and ornamental Design for a Fruit Basket, of which the following is a specification, reference being had to the accompanying drawing, forming a part thereof.

In the drawing:

I claim:

The ornamental design for a fruit basket as shown.

JAMES H. FULLER.
